EXHAUST FAN COVER

Robert E. Steiner, St. Louis, Mo., assignor to Emerson Electric Co., St. Louis County, Mo.

Filed Jan. 21, 1971, Ser. No. 108,675

Term of patent 14 years

Int. Cl. D23—04

U.S. Cl. D23—151

FIG. 1

FIG. 2

FIG. 5

FIG. 3

FIG. 4

FIG. 1 is a top plan view of an exhaust fan cover showing my new design;

FIG. 2 is a side elevational view thereof, taken from the bottom of FIG. 1, the opposite side being identical;

FIG. 3 is a bottom plan view thereof;

FIG. 4 is a side elevational view thereof taken from the right of FIG. 1, the opposite side being identical; and

FIG. 5 is a cross sectional view taken along line 5—5 of FIG. 3.

I claim:

The ornamental design for the exhaust fan cover, as shown and described.
